ANIMAL FIGURE DOLL

Anthony Chrones, 52 Wood Haven Blvd.,
North Providence, R.I. 02908

Filed May 25, 1970, Ser. No. 23,130

Term of patent 14 years

Int. Cl. D21—02

U.S. Cl. D34—2

FIG. 1

FIG. 2

FIG. 4

FIG. 3

FIG. 1 is a plan view of one side of an animal figure doll embodying my new design, the opposite side being identical;

FIG. 2 is a top plan view thereof;

FIG. 3 is a bottom plan view thereof; and

FIG. 4 is an edge view thereof, both edges being identical.

I claim:

The ornamental design for an animal figure doll, as shown and described.
